Primary Examiner—Lucy Lieberman*Attorney, Agent, or Firm*—Nies, Kurz, Bergert & Tamburro[57] **CLAIM**

The ornamental design for a plastic bottle, as shown and described.

DESCRIPTION

FIG. 1 is a side elevational view of a plastic bottle showing my new design, the opposite side being a mirror image thereof except for the conventional screw threading on the bottle neck;

FIG. 2 is a right end view thereof;

FIG. 3 is a left end view thereof;

FIG. 4 is a top plan view thereof; and,

FIG. 5 is a bottom plan view thereof.
